UNITED STATES PATENT OFFICE.

THOMAS W. BROWN, OF BELMONT, MASSACHUSETTS.

DESIGN FOR AN EGG-BEATER HANDLE.

SPECIFICATION forming part of Design No. 29,873, dated December 27, 1898.

Application filed November 9, 1898. Serial No. 695,987. Term of patent 7 years.

To all whom it may concern:

Be it known that I, THOMAS W. BROWN, a citizen of the United States, residing at Belmont, in the county of Middlesex and State 5 of Massachusetts, have invented and produced a new, useful, and original Design for an Egg-Beater Handle, of which the following is a specification, reference being had to the accompanying drawings, forming part 10 thereof.

Figure 1 is a perspective view of an egg-beater handle, showing my new, useful, and original shape or configuration thereof. Fig. 2 is a side elevation of an egg-beater provided with a handle of a new, useful, and 15 original shape or configuration.

As shown in the drawings, the leading or material feature of my design consists of the

lengthwise slot a in the angular foot a' at the base of the handle A, which is made of a single strip of sheet material enlarged at a^2 and twisted at a^3 . 20

Having described my invention, what I claim as new, and desire to secure by Letters Patent, is— 25

The design for an egg-beater handle as herein shown and described.

In testimony whereof I have signed my name to this specification, in the presence of two subscribing witnesses, on this 24th day 30 of October, A. D. 1898.

THOMAS W. BROWN.

Witnesses:

EDWARD S. BEACH,
E. A. ALLEN.
